SHUTTLE DEVICE

Knut Henrichsen, Los Angeles, Calif., assignor to North American Aviation, Inc.

Application September 14, 1953, Serial No. 379,964

13 Claims. (121—157)

This invention pertains to a shuttle device and more particularly to a hydraulically actuated shuttle device having rapid action.

This invention is intended for use where a particularly fast acting shuttle device is required. For example, there may be a reciprocal hydraulic motor which requires a fast valve action so that there will be no appreciable time taken up in supplying the actuating impulse to the motor at either end of its stroke. The shuttle device of this invention is adapted to operate such a valve and is further adapted to operate various mechanical devices. This shuttle is designed to operate when a reciprocal member reaches the end of its stroke in either direction. This reciprocal member may travel through a relatively long and slow stroke, but when the operation of the shuttle takes place the latter will pass through a relatively short stroke with great speed. This shuttle is adapted for operation by fluid pressure, preferably hydraulic fluid, and is subjected to full pressure from the fluid throughout its stroke in either direction.

Accordingly it is an object of this invention to provide a fast-acting reciprocal shuttle device.

Another object of this invention is to provide a shuttle device which moves rapidly through a short stroke when a trigger member is moved more slowly through a long stroke.

A further object of this invention is to provide a hydraulically operated shuttle adapted for operating a valve or other mechanical device.

Still another object of this invention is to provide a shuttle device which is subjected to operating forces throughout and at the termination of its stroke.

These and other objects will become apparent from the following detailed description taken in connection with the accompanying drawing in which

Fig. 1 is a sectional view of a pump and motor combination utilizing the shuttle of this invention,

Fig. 2 is a sectional view taken along line 2—2 of Fig. 1,

Fig. 3 is a sectional view taken along line 3—3 of Fig. 1, illustrating the shuttle device,

Fig. 4 is a fragmentary sectional view showing the shuttle in an intermediate position of its stroke,

Fig. 5 is a fragmentary sectional view showing the shuttle at one end of its stroke and the trigger member at the opposite end of its stroke,

Fig. 6 is a sectional view illustrating the porting action effected by the shuttle member at one end of its stroke, and

Fig. 7 is a fragmentary sectional view illustrating the porting action of the shuttle member at the opposite end of its stroke.

Referring to the drawing, the shuttle of this invention is illustrated as used with a hydraulic motor and coupled free piston pump. The action of the shuttle of this invention can best be understood by first observing the operation of the motor-pump assembly. This latter unit, as shown in Figs. 1 and 2, includes a housing 1 which is

2

provided with two inlet ports 2 and 3 and two outlet ports 4 and 5 adapted for connection with suitable fluid lines. Reciprocal within housing 1 is a free piston 6 which serves to pump the fluid from the inlet ports to the outlet ports. The inlet ports and the outlet ports all are provided with suitable spring-loaded valves 7, 8, 9 and 10 which will permit fluid flow in one direction only. Thus it is obvious that when the piston 6 is traveling to the left from the position illustrated in Fig. 1, the fluid on the left side of the piston will be forced outwardly through the port 4 and will be drawn inwardly to the right hand side of the piston through inlet port 3. At the same time valves 8 and 10 prevent fluid flow in the reverse direction through ports 2 and 5. If the piston is moved to the right fluid will be forced out through port 5 and drawn in through port 2, while valves 7 and 9 prevent reverse flow through ports 3 and 4.

For operation of cylinder 6 of the pump an extension 12 projects therefrom into cylindrical portion 13 of the housing so that end 14 of the extension forms a piston head therein. Portion 13 of the housing communicates with the inlet port 15 which is adapted for connection with a source of relatively high-pressure fluid. Projecting from the opposite side of piston 6 are two piston members 16 and 17 which extend into cylindrical portions 18 and 19 of the housing. Pistons 16 and 17 present approximately twice the effective projected piston area that is provided by piston 14. The latter piston portion is constantly under pressure from the high pressure source through inlet port 15. When pistons 16 and 17 have no pressure operating thereagainst obviously the high-pressure fluid from inlet 15 will push piston 14 to the left thereby moving large piston 6 to the left in a pumping stroke. If pistons 16 and 17 are then subjected to the high-pressure fluid, by virtue of the fact that they have twice the effective piston area of piston 14 they will overcome the force it exerts and move piston 6 back to the right in a return pumping stroke. For controlling the admission and exhaust of high-pressure fluid in the cylinders, cylinder portion 18 is provided with a port 21, while cylinder portion 19 has a port 23. In order to obtain smooth pumping action and a constant flow by piston 6, the action in porting cylinders 18 and 19 should be affected as rapidly as possible at either end of the stroke of piston 6. It is for this reason that the shuttle of this invention may be provided to actuate the valve which controls the porting of cylinders 18 and 19.

The construction and action of the shuttle can be seen in the sectional view of Fig. 3. Integrally connected to the main piston of the pump is an elongated trigger member 26. This member projects from the piston and into bore 25 of shuttle member 27 within which it terminates at an enlarged end 28 substantially the dimensions of the interior of the shuttle. Trigger member 26 has a bore 29 therethrough so that high-pressure fluid is distributed thereby to the portions of the interior of the shuttle beyond trigger lobe 28. Opening 31 extends through the remainder of the shuttle member which projects into portions of the housing defining a chamber 33. Passageway 31 thereby conducts pressurized fluid, which has been introduced into the shuttle member by the trigger member, to chamber 33 so that it reacts against end 34 of the shuttle which acts as a piston member.

Reciprocal within counter-cylinder portions 35 and 36 of the housing are counter-piston members 37 and 38 which are attached to the shuttle member in any suitable manner such as illustrated at 39 and 40 where the ends of the counter-pistons engage projecting shoulder 41 of the shuttle. The limit of the stroke through which the shuttle can operate may be defined by shoulders 43 and 44 of the housing. Counter-pistons 37 and 38 are reciprocal with the shuttle and, for all practical purposes, are

integral therewith. Counter-pistons 37 and 38 define approximately twice the effective pressure area of end 34 of the shuttle so that when counter-cylinders 35 and 36 are pressurized the force on pistons 37 and 38 will overcome that exerted by piston portion 34 and move the shuttle through its stroke to the left. Aperture 45 prevents entrapment of fluid to the left of the counter-pistons. If cylinders 35 and 36 are ported to exhaust, the force on end 34 of the shuttle will move the shuttle through its stroke to the right. By the provisions of this invention the porting of cylinders 35 and 36 will cause the shuttle to move with great rapidity when the trigger member has reached either end of its stroke.

In order to provide the fast shuttle action cylinders 35 and 36 each have actuating port means at either end thereof. Thus ports 46 and 47 communicate with cylinder 35 while ports 48 and 49 connect with cylinder 36. These ports are adapted to communicate with oppositely disposed actuating port means 50 and 51 of the shuttle. As shown in Fig. 3 the main piston 6 of the pump is midway through its stroke to the right so that end lobe 28 of the shuttle is disposed between port means 50 and 51 of the shuttle member. This means that ports 50 to the left of the lobe are subjected to high pressure from the high-pressure inlet through the bore of the trigger member, while ports 51 communicate, through bore 25, with the interior of the pump case which is at low pressure and thus acts as an exhaust. In this position ports 47 and 49 communicate with ports 51 so that the interiors of counter-cylinders 35 and 36 are ported to exhaust. This enables the high-pressure fluid against end 34 of the shuttle member to force the shuttle member to the right end of its stroke, as shown.

The operational cycle of the shuttle member can be understood by reference to Figs. 3, 4 and 5. Trigger member 26 will continue to the right from the position of Fig. 3 with the main pump piston until trigger lobe 28 has just passed ports 51 of the shuttle. At that instant ports 51 are no longer open to exhaust, but are subjected to pressurized fluid from the trigger member. High-pressure fluid then flows through the interior bore of the trigger member, and through port means 51 and ports 47 and 49 to the interior of counter-cylinders 35 and 36. Note that in this position ports 50 are closed so that no fluid passes into the counter-cylinders from these ports. When the counter-cylinders are subjected to the high-pressure fluid from ports 47 and 49 the force on the counter pistons overcomes the force exerted on end 34 of the shuttle member and begins to move the shuttle to the left. As the shuttle continues in this movement port means 51 will reach a position as shown in the fragmentary view of Fig. 4 where they no longer communicate with ports 47 and 49, but have passed beyond these ports. However, the spacing of the counter-cylinder ports is so arranged that port means 50 will be uncovered prior to the closing of ports 51 so that pressurized fluid can always enter cylinders 35 and 36 as the shuttle moves through its stroke to the left. The shuttle can thus continue in its stroke until it reaches the left end thereof as illustrated in Fig. 5. In this end position port means 50 remain in communication with ports 46 and 48, while ports 51 no longer open to ports 47 and 49. By virtue of the fact that counter-cylinders 35 and 36 are continually subjected to high-pressure fluid throughout the length and at the end of the stroke of counter pistons 37 and 38, the action of the shuttle in moving to the left will be extremely rapid, taking place almost instantaneously when compared with a relatively slow movement of main piston 6 of the pump. It should be observed that the movement of the shuttle is to the left, opposite from the direction of travel of the trigger member. The initial shuttle movement causes further opening of ports 47 and 49 so that the shuttle can rapidly pick up speed as it proceeds through its stroke. This may be contrasted with a follow-up type of valve which tends to follow the move-

ment of its actuating member and to close the port openings.

When the main pump piston then starts back through its stroke to the left, no movement of the shuttle will occur when trigger lobe 28 passes ports 51 thereof because these ports, as above stated, have been closed off. However, the instant the trigger member reaches the left end of its stroke, (shown in phantom in Fig. 5) and lobe 28 passes ports 50, there will be an open passageway through ports 46 and 48, and ports 50, to the low-pressure interior of the pump, thus providing an exhaust for counter-cylinders 35 and 36. The high-pressure fluid on end 34 of the shuttle then meets no opposition from the counter-pistons and moves the shuttle back to the right. During this movement ports 50 will pass ports 46 and 48 so that they are no longer in communication therewith. However, by proper spacing of the ports of the shuttle and the housing, ports 51 will have opened to ports 47 and 49 before ports 50 are closed. This is in the same manner that ports 50 opened prior to the closing of ports 51 where the shuttle moved to the left. This port arrangement means that the counter-cylinders are always open to exhaust throughout the movement of the shuttle in its stroke to the right, and at the end of the stroke. Again the direction of movement is opposite from that of the trigger member, and initial movement of the shuttle causes further opening of the ports. By virtue of this fact, the movement to the right is very rapid and practically instantaneous compared with the slower movement of the main piston. The pump piston then again travels to the right so that trigger lobe 28 first passes ports 50, which are closed and thus ineffective, and eventually passes ports 51, and the cycle is repeated.

In the embodiment illustrated the purpose of the rapid movement of the shuttle member, as previously stated, is to effect a valving action for cylinders 18 and 19 of the pump. Therefore, shuttle member 27 serves as a fluid distributing member for the main pump counter cylinders. As shown in Fig. 6 the interior passageway 25 through the shuttle member communicates with an additional fluid distributing port means 53. When the shuttle member is at the right end of its stroke, port means 53 communicate with ports 21 and 23 which connect with cylinders 18 and 19 respectively. This means that high-pressure fluid from the high-pressure inlet passes through the trigger member, the shuttle member, and through these ports into cylinders 18 and 19 for forcing pistons 16 and 17 to the right. This force of the high pressure-fluid, as described above, moves piston 6 through its stroke to the right. When the piston has reached the right-hand end of its stroke, and the trigger member is thus moved through its stroke to the right, the shuttle member is caused to rapidly move to the left. When this occurs ports 21 and 23 of cylinders 18 and 19 are then connected through annular port 60 with outlet passage 61, as shown in the fragmentary view of Fig. 7. Aperture 62 provides an exhaust from the housing for this fluid. Counter-cylinders 18 and 19 are thus rapidly ported to exhaust so that the high-pressure fluid against piston 14 can move main piston 6 back through its stroke to the left. The shuttle member thus provides a very rapid porting action for the counter-cylinders of the pump so that there is practically no hesitation when piston 6 reaches either end of its stroke, whereby pumping action thereof is steady and continuous.

It can be readily appreciated from the above description that it is not necessary for the shuttle member to incorporate a valve as shown and described above. The trigger member could be connected with any source of pressurized fluid and moved back and forth by any suitable means. The shuttle member 27 could be arranged to actuate, for example, an electric switch at either end of its stroke so that slower movement of the trigger member could cause rapid movement of the switch when the trigger member was at either end of its stroke. A variety

of mechanical or electrical devices could be attached to the shuttle member so that the shuttle could cause rapid movement thereof. In such case of course there would be no pump piston and no cylinders 18 and 19, and the shuttle member would not be provided with port 55.

The above detailed description, therefore, illustrates an improved, rapidly acting shuttle member whereby when a trigger member passes through its stroke in either direction, extremely rapid action of the shuttle member will take place at the ends of the stroke of this trigger member. By virtue of the fact that the ports to the shuttle member are not closed throughout and at the ends of its stroke the shuttle will continue through its stroke with undiminished velocity until it reaches the extremity thereof, thus providing the fast action of the shuttle.

The foregoing detailed description is to be clearly understood as given by way of illustration and example only, the spirit and scope of this invention being limited only by the appended claims.

I claim:

1. A shuttle device comprising a body; a shuttle member reciprocal therein; oppositely disposed fluid responsive means integral with said shuttle and operable in response to fluid pressure to effect said reciprocal movement thereof; a trigger member having means for introducing pressurized fluid into said body, said trigger member being reciprocal relative thereto, said shuttle and said body having port means therein for receiving fluid from said trigger member and distributing said fluid to said oppositely disposed fluid responsive means for operation thereof, said port means being spaced whereby operation of said fluid responsive means is obtained at opposite ends of the stroke of said trigger member and said fluid responsive means are fully operable throughout the stroke of said trigger member in either direction and at the termination thereof.

2. A device as recited in claim 1 in which said body has first and second cylindrical portions therein, and said first fluid responsive means comprises an end portion of said shuttle member closely fitted in said first cylindrical portion of said body member to thereby define a piston, and in which said second fluid responsive means comprises two counter-piston means integrally attached to said shuttle member and closely fitted in said second cylindrical portion of said body member.

3. A shuttle device comprising a body; a shuttle member reciprocal through a stroke therein, said shuttle having oppositely disposed fluid responsive means for effecting said reciprocal movement thereof, said shuttle member having a port whereby one of said fluid responsive means is adapted for continual connection with a source of pressurized fluid, the second fluid responsive means being adapted for intermittent connection with a source of pressurized fluid, said second fluid responsive means being of greater effective area than said first means whereby when said second means is subjected to pressurized fluid the force exerted thereby overcomes the force on said first fluid responsive means and moves said shuttle member in one direction through its stroke, and when said second fluid responsive means is ported to exhaust said force of said first fluid responsive means moves said shuttle member through its stroke in the opposite direction; port means in said shuttle for admitting fluid to said first fluid responsive means; actuating port means in said body and in said shuttle for admitting fluid to and exhausting fluid from said second fluid responsive means; and a trigger member reciprocal in said shuttle and cooperating with said port means, said member being adapted for connection with a source of pressurized fluid and having fluid passage means therein whereby pressurized fluid is continually admitted to said first fluid responsive means, and intermittently connected with said port means in said body and said shuttle when said trigger member is at opposite ends of its stroke for effecting said

reciprocal movement of said shuttle, said actuating port means being arranged to provide constant connection with said source of pressurized fluid and with said exhaust during said opposite movements of said shuttle and at the termination thereof.

4. A device as recited in claim 3 in which said body member is provided with a cylindrical portion dimensioned to receive an end of said shuttle member whereby said end forms said first fluid responsive means, and said body member is provided with two additional cylindrical portions each dimensioned to receive portions of said shuttle member whereby said portions form pistons comprising said second fluid responsive means, said actuating port means being axially displaced and communicating with said additional cylindrical portion.

5. A shuttle device comprising a body member, said body member having an exhaust means; a shuttle member reciprocal through a stroke therein, said shuttle member having a first piston portion responsive to pressurized fluid for moving said shuttle in one direction, and a second piston portion of greater area responsive to pressurized fluid for moving said shuttle in the opposite direction, said shuttle having a hollow interior and a first port means communicating therewith whereby said first piston portion continuously communicates with said hollow interior; and a trigger member reciprocal within said hollow interior of said shuttle, said trigger member having a bore therethrough adapted for connection with a source of pressurized fluid, and a lobe engaging said shuttle interior for distributing pressurized fluid on one side of said lobe while the opposite side thereof communicates with said exhaust, whereby said trigger member cooperates with said first port means to provide constant fluid pressure to said first piston means, said shuttle and said body having actuating port means for cooperation with said trigger lobe whereby said second piston portion communicates with said exhaust means during the entire movement of said shuttle through its stroke in said one direction, and communicates with said interior to receive pressurized fluid during the entire movement of said shuttle through its stroke in said opposite direction.

6. A device as recited in claim 5 in which said shuttle member interior includes a hollow cylindrical portion open on one end to said exhaust means, and said trigger member reciprocates therein, said lobe being dimensioned for close association therewith whereby the interior of said shuttle member is subjected to pressurized fluid on one side of said lobe, said shuttle member actuating port means being apertures therethrough disposed at axially spaced locations spaced a greater amount than said shuttle member apertures for cooperation therewith, whereby said communication is maintained through said movement of said shuttle.

7. A shuttle device comprising a body, said body having a first cylindrical means provided with actuating port means at either end thereof, and a second cylindrical means in communication with said actuating port means; an elongated cylindrical shuttle member reciprocal through a stroke in said first cylindrical means, said shuttle member having port means at either end thereof for cooperation with said body port means; piston means in said second cylindrical portion, said piston means including projecting portions engaging said shuttle member for reciprocal movement therewith; a trigger member reciprocal in said shuttle member, said trigger member having a central passageway adapted to transmit pressurized fluid to the interior of said shuttle member and having a lobe closely fitted within said interior, said shuttle member and said body having exhaust means on one side of said trigger lobe, said shuttle member including a piston portion having port means in constant communication with said interior, said piston portion having a smaller effective area than that of said piston means, whereby when said trigger member is at one end of its stroke pressurized fluid admitted by said trigger member passes through said actuating port means to said second

cylindrical portion for reacting thereagainst whereby said piston means and said shuttle member are moved through a stroke in one direction, said actuating port means being spaced whereby said actuating port means remain open throughout said stroke and at the termination thereof, and when said trigger member is at the other end of its stroke said port means communicate with said exhaust means whereby said second cylindrical portion is exhausted of said fluid, and pressure against said piston portion moves said shuttle through a return stroke in 10 the opposite direction, said port means remaining open to said exhaust throughout said return stroke and at the termination thereof.

8. A device as recited in claim 7 in which said actuating port means for said shuttle member comprise axially 15 spaced radially disposed aperture means, and said actuating port means for said body member comprise aperture means axially spaced a greater distance than said shuttle member actuating port means, whereby said continual port openings are maintained during said movement of 20 said shuttle member.

9. A shuttle device comprising a body member having an exhaust, said body member having actuating port means therein; a shuttle member reciprocal within said body, said shuttle member having actuating port means for cooperation with said body member actuating port means, and having port means communicating with said exhaust, said shuttle member having a first pressure area on one side thereof and a second and larger pressure area on the opposite side thereof, a trigger member in said body member in engagement with said shuttle member, said trigger member projecting beyond said body for external operation thereof between two extreme positions, said trigger member being adapted for connection with a source of pressurized fluid whereby said fluid is continuously transmitted to said first pressure area, and said actuating port means interconnect said second pressure area with said pressurized fluid when said trigger member is in one extreme position, and interconnect said second pressure area with said exhaust when said trigger member is in the other extreme position whereby when said second pressure area is connected with said exhaust, said pressurized fluid on said first pressure area urges said shuttle through a stroke in one direction, and when said second pressure area is subjected to pressurized fluid said fluid urges said shuttle through a stroke in the opposite direction, said actuating port means being spaced whereby said connection to said exhaust is maintained throughout said stroke in said first direction and said connection to said pressurized fluid is maintained throughout said stroke in said opposite direction.

10. A device as recited in claim 9 in which said port means are spaced whereby said fluid is transmitted through port means at one end of said shuttle and said body member during the first part of the stroke of said shuttle, whereupon such movement closes said port means and opens the port means at the opposite end of said shuttle and body member, said opening taking place prior to said closing of said firstly mentioned port means, said lastly mentioned port means remaining open throughout said stroke and at the termination thereof.

11. A shuttle device comprising a body; a shuttle reciprocal in said body, said shuttle having a bore therethrough, one portion of said shuttle forming a piston communicating with said bore and responsive to fluid pressure for moving said shuttle in one direction; a trigger member reciprocal through a stroke in said bore, said trigger member having aperture means therethrough and a lobe complementary to said bore, said trigger member being adapted for connection with a source of pressurized fluid whereby said fluid passes through said member to said shuttle member and engages said piston portion thereof; port means in said body; port means in said shuttle communicable therewith, said port means in said body communicating with counter-cylinder means therein;

5 piston means reciprocal in said counter-cylinder means and connected with said shuttle, said counter-cylinder piston means having greater area than that of said shuttle piston portion whereby when pressurized fluid is admitted into said counter-cylinder means said counter-cylinder piston means overcome the force of said fluid on said shuttle piston portion and move said shuttle in one direction, and when said counter-cylinder means are ported to exhaust said fluid against said piston portion moves said shuttle member in the opposite direction, said trigger member being operable at opposite ends of its stroke to conduct pressurized fluid to said port means, and to connect said port means with said exhaust, said port means being spaced to remain open the entire length and at the end of the stroke of said shuttle in either direction.

12. A shuttle device comprising a body member, said body member having an exhaust means; a shuttle member reciprocal through a stroke in said body member; a trigger member reciprocal through a stroke in said body member, said trigger member having a lobe associated with said shuttle member and having a portion projecting from said body for external actuation thereof, said trigger member having passage means therethrough adapted for connection with a source of pressurized fluid whereby 25 pressurized fluid is transmitted to one side of said lobe, and the other side thereof communicates with said exhaust means; said shuttle member having a pressure area on one side thereof and port means communicating therewith whereby said pressure area is constantly subjected to fluid pressure from said trigger member, said shuttle member having a second pressure area on the other side thereof; said body member and said shuttle member having port means communicating with said second pressure area whereby when said trigger member is at one end of its 30 stroke said second pressure area receives pressurized fluid from said port means for moving the said shuttle member through its stroke in one direction, and when said trigger member is at the other end of its stroke said second pressure area communicates through port means with said 35 exhaust whereby said pressure on said first pressure area moves said shuttle member through its stroke in the opposite direction, said actuating port means being arranged whereby constant communication with said pressurized fluid is maintained therethrough during the entire movement of said shuttle member through its stroke in said 40 one direction, and constant communication with said exhaust means is maintained through said port means the entire length of the stroke of said shuttle in said opposite direction.

13. A shuttle device comprising a body member having an exhaust, and a first and a second cylindrical portion; a shuttle member reciprocal within a complementary portion of said body member, said shuttle member having a hollow interior communicating with said exhaust; a trigger member in said shuttle member and reciprocal through a stroke relative thereto, said trigger member having an enlarged lobe closely fitted within said interior of said shuttle member, said trigger member projecting from said body member for external actuation thereof and being provided with a fluid passage means therethrough whereby said member is adapted to be connected with a source of pressurized fluid for transmitting said fluid to the interior of said shuttle beyond said lobe whereby said interior beyond said lobe is subjected to said pressurized fluid, and said interior on the opposite side of said lobe is connected with said exhaust, said shuttle member having an end thereof closely fitted with said first cylindrical portion of said body member, and provided with fluid passage means interconnecting said hollow interior and said end portion whereby said end portion comprises a first piston constantly subjected to said pressurized fluid, said shuttle member having attached thereto a second piston portion of greater area than said 55 first piston closely fitted within said second cylindrical portion of said body member.

portion of said body member, said shuttle member having axially displaced actuating port means communicating with said hollow interior, and said body member having axially displaced actuating port means for cooperation therewith and communicating with said second cylindrical portion whereby when said trigger member is at one end of its stroke said hollow interior is in communication with said exhaust and said actuating port means interconnect said second cylindrical portion with said exhaust whereby said fluid pressure against said first piston moves said shuttle through its stroke in one direction, and when said trigger member is at the opposite end of its stroke said hollow interior portion is subjected to said pressurized fluid whereby said actuating port means connect said interior and said second cylindrical portion for subjecting said second piston portion to said pressurized fluid and moving said shuttle through its stroke in the opposite direction, said actuating port means in said body

member being spaced apart a greater amount than said actuating port means in said shuttle member and disposed whereby constant communication with said exhaust is maintained throughout said movement of said shuttle in said one direction and at the termination thereof, and constant communication with said pressurized fluid is maintained throughout said stroke of said shuttle member in said opposite direction and at the termination thereof.
